LAMP CIRCUIT

Frank Furedy, Chicago, Ill., assignor to Sun-Kraft, Inc., Chicago, Ill., a corporation of Illinois

Application December 16, 1940, Serial No. 370,271

8 Claims. (Cl. 176—124)

This invention relates to a circuit for energizing a gaseous discharge lamp, particularly an ultra-violet or like therapeutic lamp.

It is an object of this invention to provide an electronic tube oscillator circuit of greater simplicity and compactness and less expensive from the manufacturing point of view so that the parts of such an oscillator circuit may be included in a restricted area and hence used to energize the gaseous discharge tube of an ultra-violet floor or table lamp.

It is a further object of the invention to provide a one tube high frequency oscillating circuit capable of energization from the ordinary house circuit or circuit of similar voltage without use of a power transformer and which shall be capable of supplying a relatively large amount of power to energize an electrodeless gaseous discharge tube such, for example, as a fluorescent lamp or ultra-violet ray lamp for therapeutic treatments or other analogous use.

A further object of the invention is to provide a circuit employing only a single electronic tube for energizing the gaseous discharge tube from either an alternating current or a direct current source of standard house lighting voltage.

Applicant's invention contemplates the provision of a high frequency power supply circuit capable of supplying power up to approximately eighty watts and which at the same time is of such simplicity in its number of parts that it may be mounted within an area of small volume, as, for example, within a hemispherical bowl or lamp base of a diameter of the order of five inches.

Other and further objects and advantages of the invention will be apparent from the following description when taken in connection with the accompanying drawing, wherein the single figure is a schematic drawing of a circuit embodying the invention.

As shown in the drawing, the lamp 2 which may be a quartz ultra-violet ray lamp or a fluorescent lamp, comprises an electrodeless gaseous discharge tube exhausted to a high vacuum, filled with mercury vapor, argon, neon, helium and krypton or other suitable rare gases and with a globule 4 of mercury, after which the lamp is sealed off. High frequency voltage for the excitation of the lamp is supplied thereto by external clips, terminals or electrodes 6 which mount the lamp in the reflector as described in my copending application, Serial No. 347,257, filed July 24, 1940.

A voltage is supplied to the terminals 6 through 55

the long leads 8 and 10 which, in the lamp shown in said copending application, are of the order of thirty inches in length and are connected at their outer ends to plug terminals 12 fitting into the socket terminals 14 in the output of the high frequency generating or oscillating circuit 16. The circuit 16 comprises a thermionic vacuum tube 18. The tube 18 comprises a pair of cathodes 20 and 22, a pair of plates or anodes 24 and 26, a control grid 28, a screen grid 30, and a pair of series connected heater filaments 32 and 34. The series connected heater filaments 32 and 34 are connected across the house circuit supply lines L—1 and L—2 or across other supply lines of similar voltage. The plate 24 is connected to the supply line L—1 by the wire 36. The cathode 20 is connected by the wire 38 to the screen grid 30. The cathode 22 is connected by the wire 40 to the supply line L—2. The control grid 28 is coupled to the cathode 22 through a grid resistor 42 which is connected to the control grid by a wire 44 and to the supply line L—2. The control grid is also coupled to the end 50 of an air core induction coil or inductance 52 by the wire 44 and a wire 54 in which is interposed a condenser 56.

The plate or anode 26 is connected by a wire 58 to an intermediate tap 60 of the coil 52. The screen grid 30 is connected by the wires 62 and 64 to an intermediate tap 66 of the coil 52 and to the condenser 48.

The end 68 of the air core induction coil or inductance 52 is connected to the end 50 of the coil by the wires 70 and 72.

The terminals 14 of the output socket are connected by the wire 72 and the wire 74 to the end 50 and the intermediate tap 60 of the coil 52.

In a preferred construction the tube 18 is a high vacuum, rectifier-beam power amplifier tube No. 117-L-7. In this preferred construction, the circuit constants have the following values:

1. The grid resistor, 42—10,000 ohms;
2. The grid condenser, 56—.00025 microfarads;
3. The condenser 48 is an electrolytic 150 to 450 volt condenser of the value of four microfarads;

4. The induction coil 52 is of a number 23 cotton and enamel magnet wire of 72 turns wound on a $\frac{1}{8}$ inch tube, and the tap 66 is located at three turns from the end 50 and the tap 60 located at three turns from tap 66.

In operation, when the timing switch 76, of conventional construction and in the line L—1, is closed, current passes directly through the series

connected filaments 32 and 34 of the tube 18. When the line L-1 is positive, current passes through the wire 36, through the plate 24, the cathode 20, wire 38 and wires 62 and 64 to charge one plate of the condenser 48 which has its other side connected to the line L-2. In parallel to the condenser 48 current also passes from the wire 38 through the wire 62, tap 66, three turns of the coil 52, tap 60, wire 58, plate 26, the cathode 22 and the wire 40 to the supply line L-2.

As the charge is built up on the condenser 56 and then leaks away, a high frequency current is produced in the induction coil 52 at a frequency in the order of 550 kilocycles, sufficient to excite the lamp 2 to luminescence, but the rays within the lamp do not extend completely from end to end of the tube and a slight flickering is observed. The portion of the induction coil 52 between the tap 60 and the end 68 when connected as shown reenforces the current from the portion of the coil between the end 50 and the taps 60 and 66 and causes the rays to extend completely from end to end of the lamp tube 2 and with a steady glow.

The circuit shown in the drawing operates either on alternating current or direct current. In the case of direct current the circuit must be connected to the supply lines so that the cathode 22 is connected to the negative supply line and the plate 24 to the positive supply line.

The tube 2 may also be energized by placing it in the magnetic field proximate to or within the coil 52.

It is obvious that various changes may be made in the specific embodiments of the invention set forth for purposes of illustration without departing from the spirit of the invention. Accordingly the invention is not to be limited to the specific embodiments shown and described but only as indicated in the following claims.

The invention is hereby claimed as follows:

1. A high frequency oscillating circuit for energizing a gaseous discharge tube comprising an electronic tube having plate, cathode and grid electrodes, a source of voltage, an induction coil, a portion of said coil and said plate and cathode electrodes being connected in series across said source, a condenser connected in shunt with said coil portion and said plate and cathode electrodes, an impedance connected between said grid and cathode electrodes and a circuit shunting said impedance, said circuit including a condenser in series with another portion of said induction coil.

2. A high frequency oscillating circuit for energizing a gaseous discharge tube comprising an electronic tube having plate, cathode and grid electrodes, a source of voltage, an induction coil having a portion between spaced taps connected to one of said plate and cathode electrodes and one side of said source, the other of said plate and cathode electrodes being connected to the other side of said source, another portion of said induction coil being connected to said first portion and to one of said grid and cathode electrodes, and an output circuit from said coil to said gaseous discharge tube and in which said gaseous discharge tube is connected in series with both of said portions of the induction coil.

3. A high frequency oscillating circuit for energizing a gaseous discharge tube comprising an electronic tube having plate, cathode and grid electrodes, a source of voltage, an induction coil, a portion of said coil and said plate and cathode electrodes being connected in series across said

source, another portion of said induction coil being connected across said grid and cathode electrodes, and an output circuit from said coil to said gaseous discharge tube and in which said gaseous discharge tube is connected in series with both of said portions of the induction coil, said induction coil having a third portion directly connected in shunt to said first and second portions in the output circuit to said gaseous discharge tube.

10 4. A circuit for energizing a gaseous discharge lamp from a standard alternating or direct current low voltage source, comprising an electronic tube having rectifying electrodes and having plate, cathode and grid electrodes; an induction coil, a portion of said coil, said rectifying electrodes and said plate and cathode electrodes being connected in series across said source; and said induction coil having a portion connected to the first portion of said coil and to one of said grid and cathode electrodes.

15 5. A circuit for energizing a gaseous discharge lamp from a standard alternating or direct current low voltage source, comprising an electronic tube means having rectifying electrodes and additional plate, cathode and grid electrodes; an induction coil, a portion of said coil, said rectifying electrodes, and said plate and cathode electrodes being connected in series across said source, a power condenser in shunt to the series circuit of the first portion of said coil and said plate and cathode electrodes, a connection from said coil to said grid, and a resistor connected between said grid and cathode electrodes.

20 6. A circuit for energizing a gaseous discharge lamp from a standard alternating or direct current low voltage source, comprising an electronic tube having rectifying electrodes and additional plate, cathode, screen grid, and control grid electrodes; an induction coil; one of said rectifying electrodes being connected to one side of said source, and the other of said rectifying electrodes being connected to one of said screen grid and plate electrodes; said coil having spaced intermediate taps, one of which is directly connected to said other rectifying electrode, the other of said taps being connected to the other of said plate and screen grid electrodes; a grid condenser connected to one end of said coil and to said control grid; a resistor connected between said grid and cathode electrodes; a connection from said cathode electrode to the other side of said source; a power condenser connected between said other side of said source and said other rectifying electrode; and a direct conductive connection between the opposite ends of said coil.

25 7. A circuit for energizing a gaseous discharge lamp from a standard alternating or direct current low voltage source, comprising an electronic tube having rectifying electrodes and additional plate, cathode, screen grid, and control grid electrodes; an induction coil; one of said rectifying electrodes being connected to one side of said source, and the other of said rectifying electrodes being connected to one of said screen grid and plate electrodes; said coil having spaced intermediate taps, one of which is directly connected to said other rectifying electrode, the other of said taps being connected to the other of said plate and screen grid electrodes; a grid condenser connected to one end of said coil and to said control grid; a resistor connected between said grid and cathode electrodes; a connection from said cathode electrode to the other side of said source; a power condenser connected between said other side of said source and said other rectifying elec-

trode; a direct conductive connection between the opposite ends of said coil; and an output circuit from said coil to said lamp and including a lead from the connected ends of said coil and a lead from one of said intermediate taps.

8. A circuit for energizing a gaseous discharge tube comprising a source of voltage, an electronic tube having plate, cathode and grid electrodes, an induction coil, a circuit including in series a portion of said coil and said plate and cathode elec- 10

5 trodes, a condenser connected in shunt to that portion of the circuit that includes the coil portion in series with the plate and cathode electrodes, and a second circuit in conductive shunt to said portion of said coil and including in series another portion of said coil, and a leak impedance, said leak impedance being directly connected at its opposite ends to said grid and cathode electrodes.
